To all whom it may concern:

Be it known that I, CHARLES P. MOSHER, a citizen of the United States, residing in Philadelphia, Pennsylvania, have invented and produced a certain new and original Design for a Sad-Iron Handle, of which the following is a specification.

My design for a sad-iron handle is clearly illustrated in the accompanying drawing, which represents the handle in perspective.

The essential feature of the design is the circular side extension connected to the center of the base of the handle.

D is the base of the handle, having a hand-
hold D', and projecting laterally from the cen-

ter of the handle is an arm d, connected to the circular portion D², giving the effect clearly illustrated in the drawing.

I claim—
